CLAIM

The ornamental design for a electronic game housing,
as shown and described.

DESCRIPTION

FIG. 1 is a perspective view of an electronic game housing showing our new design;
FIG. 2 is a front elevational view thereof;
FIG. 3 is a reduced scale rear elevational view thereof;
FIG. 4 is a reduced scale left side elevational view thereof; the right side elevational view being a mirror image thereof;
FIG. 5 is a top plan view thereof; and,
FIG. 6 is a bottom plan view thereof.

FIG. - 1
